UNITED STATES PATENT OFFICE.

JOSEPH A. ALBERS, OF NORWOOD, OHIO.

CARTON.

1,412,155.

Specification of Letters Patent. Patented Apr. 11, 1922.

Application filed July 12, 1920. Serial No. 395,501.

To all whom it may concern:

Be it known that I, JOSEPH A. ALBERS, a citizen of the United States of America, and resident of Norwood, in the county of Hamilton and State of Ohio, have invented a new and useful Improvement in a Carton, of which the following is a specification.

An object of my invention is to provide a carton for combined packing and display purposes.

Another object is to produce a carton provided with an element which acts to close the device or for holding it in a display position.

15 These and other objects are attained by the means described herein and disclosed in the accompanying drawing in which:

Fig. 1 is a plan view of an unassembled blank embodying my invention.

20 Fig. 2 is an enlarged perspective view, some parts being broken away of an assembled carton embodying my invention.

Fig. 3 is a perspective view on reduced scale of a closed carton.

25 The carton body A comprises a top b, front c, bottom d, and back e. The enumerated parts are set off from one another by the scored line b', c' and d'. A cover a is attached to the top b and is set off therefrom by the scored line a'. The cover a and top b may be dispensed with if desired. The tongue f is attached to the back e and is set off therefrom by the scored line e'. When the cover a and top b are dispensed with, the tongue is 35 made of such size and shape that it will serve as a cover for the carton body. The sides g are attached to the top b and are set off from the top by scored lines g' and have the lugs g' formed upon them and set off by scored lines

40 g'', lugs c' are attached to the front c and are set off therefrom by the scored line c'', the lug e' is attached to the back e and set off therefrom by the scored lines e''. A slot b'' is formed between the top b and the front c

45 on the scored line b' and a slot d'' is formed in the bottom d. The central part of the top b is punched out thereby forming a central perforation b''. The tongue f comprises a flange f', flap f'', lap f''' and a lug f''. The

50 flap is set off from the flange and the lap by the scored lines f'' and f''' respectively. The lug f'' is attached to the lap f''' and is set off therefrom by the scored line f''. The lug f'' is adapted to pass through slots b'' and d''.

55 The carton is set up as follows:

The front c is bent at right angles to the

top turning on the scored line b', bottom d is then turned on the scored line c' and at right angles to the front c so that it will lie immediately below the top b. The back e 60 is then bent toward the top b, turning upon the scored line d''. The flange f' on the tongue f is secured to the cover a by any means, for example by being glued thereto. The lugs c'' and e'' are then bent toward one 65 another, turning upon the scored lines c''' and e''' respectively. The sides g are then bent downward over the lugs e'' and c'' and bent upon the lines g''. The lugs g'' are bent upon scored lines g''' and are inserted 70 between the top b and the bottom d, engaging the bottom d.

When articles are packed in the carton for shipment the cover a and tongue f are bent forward on scored lines a' and e' respectively so that they will lie over the top b and will close the perforation b'' in the top. The lug f'' on the end of the tongue is inserted in the slot b'' thereby closing the 75 carton. When the carton is to be used for display purposes the lug f'' is withdrawn from the slot b'', the flap f'' is bent backward upon scored line f'', the lap f''' is bent downward upon scored line f'''. The cover a and the tongue f are then bent backward 80 upon scored lines a' and e' respectively, until the lug f'' can be inserted in the slot d'' in the bottom d, thereby causing the flap f'' and the lap f''' to perform the function of 85 legs or struts supporting the carton body in 90 an inclined position. The flap f'' besides serving as a strut, supports the cover at an angle to the top b, so that any advertising matter thereon will be held up to view.

The shoulders f'' formed on the lap f''' engage the carton adjointly to the slot b'' and d'', thereby limiting the extent to which the lug will enter such slots, and also prevents the structure from collapsing to a prone position when articles are placed 95 therein.

The weight of any articles placed within the carton when set up for display will be transmitted to the flap f'' and lap f''' of the tongue, both of which act as legs and cooperate in supporting the carton in such position. The shoulders f'' transmit some of the weight of the packed articles to the lap f''', and the flange f' transmits the balance of such weight to the flap f''. The articles in 105 110 the carton bearing downward on the lug f'' prevent the separation of the parts.

What I claim is:

1. The combination with a carton body of a cover, a tongue adapted in one position to secure the cover in a closed position and in 5 a second position to support the body of the carton at an angle and to support the cover at an angle above the body of the carton.
2. The combination with a carton body having a perforated top, of a cover adapted 10 to lie over the perforated top, and a tongue adapted in one position to secure the cover in a closed position upon the perforated top, and in a second position to support the body of the carton at an angle and to support the 15 cover at an angle to the top.
3. In a carton the combination of a body having a slotted bottom, a top and front having a slot between them, said front being lowermost when the box is in display position, a tongue adapted either to be folded backward adjacent to the back of the carton or to be extended forward across the top, said tongue having a lug which is adapted 20 to enter the slot in the bottom to incline the carton body or to enter the slot between the 25 top and the front and to hold the top closed.
4. In a carton the combination with a car-

ton body comprising a perforated top, a front, a slotted bottom, a back, and sides, and having a slot between the top and the 30 front, of a cover attached to the top and adapted to extend over the perforation in the top, and a tongue comprising a flange secured to the cover, a flap, attached to the flange, a lap attached to the flap, and a lug 35 on the lap, the flap and lap being adapted to extend across the cover when the cover extends over the perforation in the top, and the lug being adapted to be inserted in the slot between the top and the front and to 40 secure the cover, flap and lap upon the top, said flap, lap and lug being also adapted to be moved to a position to the rear and bottom of the carton body, such flap and lap forming struts adapted to support the body 45 in an inclined position, and to support the cover at an angle to and above the cover, the lug being adapted to be inserted in the slot in the bottom and to secure the parts 50 in the aforesaid positions.

In witness whereof, I have hereunto subscribed my name this 3rd day of July, 1920.

JOSEPH A. ALBERS.
